ERIC HERMAN ODERMAN, OF WAYNESBORO, PENNSYLVANIA, ASSIGNOR TO FRICK COMPANY, OF WAYNESBORO, PENNSYLVANIA, A CORPORATION.
OIL-SPLASH SHIELD FOR ENGINE-CRANK CASINGS

1,191,217.

Specification of Letters Patent. Patented July 18, 1916.

Application filed November 20, 1915. Serial No. 62,568.

To all whom it may concern:

Be it known that I, ERIC HERMAN ODERMAN, a citizen of the United States, residing at Waynesboro, Franklin county, and State of Pennsylvania, have invented and discovered certain new and useful Improvements in Oil-Splash Shields for Engine-Crank Casings, of which the following is a specification.

My said invention consists in certain improvements in the construction and arrangement of parts of the interior of the crank casing for engines, particularly steam engines, or compressors, and it relates especially to the construction and arrangement of baffles, or splash shields, designed for regulating the amount of oil splash delivered to the cylinders and the cross-head pin from the oil bath contained in the casing, and protecting certain parts of said casing, whereby said advantages in construction and operation are secured, all as will be hereinafter more fully described and claimed.

Referring to the accompanying drawing, which is made a part hereof, and on which similar reference characters indicate similar parts, Figure 1 is a central longitudinal section through a vertical engine casing of the type for which my invention is especially intended, and Fig. 2 a cross-section through the same, the piston and the connection between the piston and the crank-shaft being shown in Fig. 2, but omitted in Fig. 1.

In said drawings the portions marked A represent the casing, B the crank-shaft, C the end splash shields, and D the center splash shield.

The casing A is of a common type of construction, having an inclosed crank casing in its lower end and the engine cylinders extending vertically above said inclosed crank casing. The ends of the crank casing are formed bored out and closed with heads 11 and 12 respectively, in which are formed bearings for the ends of the crank-shaft B, said bearings being lined with appropriate lining material 13.

The crank-shaft B is or may be any desired form or type of compound crank-shaft with a number of cranks corresponding to the number of cylinders of the engine. The engine portions 14 are mounted in the cylinders 10, and each is connected by a pitman 15 with the appropriate wrist 16 of the crank-shaft. The splash shields 6 are in the

form of annular flanges on the inner faces of the heads 11 and 12, and extend inwardly for a distance to cover the angle of the crank-shaft between the bearings and the wrists 16. These flanges or shields may be cast in piece with the heads 11 and 12, or formed as separate parts appropriately attached thereto as shown.

The shield D is cylindrical in form, mounted on a cast base 17, and is adapted to surround the part of the crank-shaft between the wrists 16, being of a size to pass over the central portion of said shaft or permit the shaft to be slid longitudinally therein, or vice versa. By this means the shield can be adjusted longitudinally in the crank casing to bring it to the desired relation with the crank, and may be secured in such relation by any appropriate means, as will be readily understood.

A bath of oil is contained in the lower part of the casing as indicated, the top of the oil bath reaching slightly above the lower dip of the cranks of the crank-shaft.

In operation, the throw or splash of the oil from the oil bath upwardly will largely strike the shields C and D and will be prevented from going over into the cylinders, or being thrown outwardly against the wall of the crank case. The shields are stationary, and do not revolve with the shaft, and may be adjusted in relation to the shaft and in relation to its cranks to secure the best results.

Having thus fully described my said invention, what I claim as new and desire to secure by Letters Patent, is:

1. The combination with an engine crank case of oil splash shields consisting of cylindrical parts surrounding the portions of the crank-shaft between the wrists thereof and supported from the crank casing, substantially as set forth.

2. In an engine, the combination with the crank casing and a crank-shaft mounted therein, of oil splash shields also mounted in said crank casing and each arranged to surround a crank between the wrists or bearings thereof, the central or intermediate shield being mounted to have an independent longitudinal adjustment in relation to the crank-shaft, substantially as set forth.

3. In an engine, the combination of an oil-containing crank casing, a crank-shaft mounted therein, oil splash shields in the

form of annular flanges surrounding the ends of said crank-shaft adjacent to the respective heads of the crank casing and secured to said heads, and another oil splash 5 shield of cylindrical form surrounding the central portion of said crank-shaft, and mounted on an independent support within said crank casing, substantially as set forth.

In witness whereof, I have hereunto set my hand and seal at Waynesboro, Pennsylvania, November, A. D. nineteen hundred and fifteen. 10

ERIC HERMAN ODERMAN. [L. S.]
